Pierre Barnes
ATTORNEY

UNITED STATES PATENT OFFICE

JOHN D. GUISS, OF SEATTLE, WASHINGTON

HEADLIGHT-POSITIONING APPARATUS

Application filed January 15, 1929. Serial No. 332,607.

This invention relates to light-beam testing devices for use in directioning spotlights and headlights of automobiles.

The object of the invention is to provide devices of this character which will be more simple in construction and more conveniently utilized than others hitherto in use.

Another object is to provide light beam testing devices which is peculiarly adapted for use in service stations or garages, and which may be quickly brought into and out of its operating position.

More specific objects and advantages of the invention will appear in the following description.

The invention consists in the novel construction, adaptation and combination of parts hereinafter described and claimed.

In the accompanying drawing,—

Figure 1 is a front elevation of devices embodying my improvements shown applied to the wall of a building, and in its extended or display relation; Fig. 2 is a side elevation of Fig. 1 with the building structure shown in section; Fig. 3 is a fragmentary front elevation of parts of the invention shown in Fig. 1 to a larger scale; and Fig. 4 is a vertical section taken substantially on the line 4—4 of Fig. 3.

The present invention comprises a rectangular curtain 5 of cloth or other suitable flexible material secured along its upper edge to a roller 6. This roller is of the self winding (Hartshorn) type, containing a spring, not shown, to effect rotation of the roller for winding the curtain thereabout in the direction in which it is represented in the drawing. Said roller is also provided with the usual controls, not shown, whereby the curtain may be stopped at a desired elevation.

Said curtain roller is rotatably mounted in brackets 7 secured to the ends of a horizontal supporting bar 8 which, in turn, may be nailed or otherwise secured to a building wall 9.

Intermediate its length the bar 8 has connected thereto a vertical bar 10, hereinafter termed the post, whose lower end preferably bears upon the floor surface 11.

For convenience in packing for transportation and storage, the post 10 is made detach-

able from the bar support 8 as by the provision in the latter of a post receiving socket 12 between two face plates 13. The post 10 has marked thereon a scale 14 of numbers as "24", "25", "26", etc., located at distances in inches from its lower end, of the floor plane 11, designated by the respective numbers. The curtain has marked thereon a horizontal or height line 15 and a vertical or centering line 16 crossing said horizontal line medially of the width of the curtain and in front of the post 10 respectively. At the intersection of said lines, however, the curtain is formed with a sight aperture 17 through which the scale numbers upon the post may be successively observed for regulating the curtain to have the height line 15 positioned at a selected elevation—say 34 inches, for example—above the plane of the floor, which positioning would be indicated by the corresponding scale number, as "34", appearing at the sight aperture.

The curtain is provided, moreover, with horizontal scales 18 located in proximity to the height line 15 and disposed symmetrically with respect to the centering line 16.

The divisions of the scales 18 are denoted by numbers as "16", "20", "24", etc., which designate twice the distances, in inches, the respective scale marks are from said centering line. 19 represents a pair of rods, one rod at each side of the curtain, the upper end of the rods being formed to provide each with a hook 20 which is engageable over the upper part of the curtain which is wound upon the roller.

As best shown in Fig. 4, a rod 19 is hung by its hook to be in a plane substantially tangent to the front of the roll or wound-up portion of the curtain and thus, when illuminated by the light beams of the lamp of an automobile, casts a shadow upon that part of the curtain to bisect the respective curtain scale 18.

For testing the headlights of an automobile, the car is positioned on the floor 11 at a predetermined distance—say, twenty-five or thirty feet—in front of the curtain, and with its longitudinal axis in the plane of the centering line 16. Thus arranged the curtain is

raised or lowered, as required to bring the height line 15 at an elevation—indicated by the scale 14—above the floor which will correspond with the proper intersection of the 5 light beams projected from the headlights of the car. With the curtain thus regulated, the height line 15 is utilized to indicate with respect to spots of light projected from the headlights whether or not the headlights are 10 suitably set to afford the requisite downward slant or inclination of the light beams.

If found by such a test to be improper the same may be corrected—with reference to the height line—by adjusting vertically the 15 headlights.

The regulation of headlights horizontally is accomplished with reference to the rods 19 in conjunction with the respective scales 18 against which shadows of the respective 20 rods are cast by the light beams from the headlights.

In practice a schedule may advantageously be used giving elevations of headlights for various makes of cars, and also allowances for alterations in the "trim" or horizontal inclinations, due to the load or absence of load for the respective cars.

The construction of the illustrated embodiment of the invention and the manner 30 of using the same will it is thought be understood from the foregoing description.

What I claim is:—

1. In apparatus of the character described, a vertically adjustable curtain having horizontally arranged scales thereon, devices provided in spaced relation in front of said curtain and movable transversely thereof and adapted to cast shadows on the curtain and across the scales by means of the light 40 beams from the headlights of an automobile, and means for supporting said devices.

2. In apparatus of the character described, the combination of a curtain having thereon a horizontal mark and horizontally disposed measuring scales, said curtain being arranged for vertical adjustment, a curtain support including a vertical member having scale markings thereon located behind the curtain, said curtain having a sight opening therein through which is visible one of said vertical scale markings whereby the curtain may be regulated for positioning said horizontal mark at different elevations, and indicating devices disposed in 50 front of the curtain and movable transversely of the latter into selected distances apart and with respect to the horizontally arranged scales.

3. In apparatus of the character described, a vertically adjustable curtain having thereon a horizontal mark and horizontally disposed measuring scales, said mark being adapted to indicate the elevation relative to a stationary scale and said curtain 65 scales being adapted to indicate the hori-

zontal directional relations respectively of the headlights of an automobile, and means for supporting the curtain to retain the mark thereon at various elevations selectively.

4. In apparatus of the character described, the combination with a rotary roller, and a curtain connected to the roller to be rolled thereabout, said curtain having markings thereon, a rigid support for said roller, of means depending from said roller and adapted to indicate the disposition of light beams relative to said markings, said means being shiftable transversely of the curtain into selected positions with respect to said markings.

Signed at Olympia, Washington, this 19th day of December, 1928.

JOHN D. GUISS.
